UNITED STATES PATENT OFFICE.

FERDINAND KERN, OF NEWARK, NEW JERSEY, ASSIGNOR OF THREE-FOURTHS TO HEILNER & STRAUSS, OF NEW YORK, N. Y.

SHUTTLE-ACTUATING MECHANISM FOR DUPLEX-NEEDLE SEWING-MACHINES.

SPECIFICATION forming part of Letters Patent No. 447,880, dated March 10, 1891.

Application filed September 7, 1889. Serial No. 323,262. (No model.)

To all whom it may concern:

Be it known that I, FERDINAND KERN, of Newark, New Jersey, have invented a new and useful Improvement in Sewing-Machines, 5 of which the following is a specification.

This invention consists in an improvement on the machine described in an application filed by me February 21, 1889, Serial No. 300,791, and it will be only necessary for me 10 to describe herein those parts in which the present machine differs from that described in said application. These differences reside in the means by which the mechanism for driving the supplemental shuttle is made extensible. 15

In the drawings, Figure 1 is an inverted plan view of the machine. Fig. 2 is a vertical section showing principally those portions below the plate. Fig. 3 is a detail showing 20 disks *h* and *i*.

a is the table of the machine.

b is the presser-foot.

c is the needle-bar.

d is one needle, and *d'* is the other. The rotating shuttles face each other at *e* and *e'*, respectively, being mounted at the ends of their 25 respective driving-shafts *f* and *f'*.

I will now describe the mechanism employed in driving the shafts *f* and *f'*.

30 *g* is the connecting-rod depending from the main shaft in the bracket-arm of the machine. This connecting-rod terminates at its lower end in two branches *g'* and *g''*.

h and *i* are two disks mounted, respectively, 35 upon the end of the shaft *f* and of the sleeve *j*. These disks are slotted at *h'* and *i'* to receive the pins *g'* and *g''* of the connecting-rod *g*.

j' is a short shaft for connecting the sleeves *j* and *j''*. It has its bearings in the hanger *k*, 40 and in operation is fixed to the sleeves *j* and *j''*, so as to move as in one piece therewith. The shaft *l* has its bearings in the hangers *k'*, *k''*, and *l''*. It enters the sleeve *j''*, forming a telescope-joint therewith, prevented from

turning by the set-screws *l'* and *l''*, adapted to 45 slide in the longitudinal slots *l''* and *l''* of the sleeve *j''*. The supplemental table *a'*, carrying shaft *f'* and its shuttle, is supported and movable, as described in said application, and the same is true of the connections between 50 the shafts *f'* and *l*. It will be observed, however, that the shafts *f* and *l* here have independent connections with the connecting-rod *g*, and that the mechanism for driving the supplemental shuttle is made extensible by 55 the telescope-joint already referred to.

The manner in which I prefer to mount the bobbins is described in Letters Patent to me, No. 436,002, dated September 9, 1890.

I do not desire to limit myself to the details 60 or form of construction.

I claim—

1. In a duplex-needle machine, in combination with the shafts by which the shuttles are actuated, the forked connecting-rod, whereby 65 motion is transmitted from the needle-bar shaft to both shuttle-shafts, substantially as set forth.

2. In a duplex-needle machine, in combination, the needle-actuating shaft, the shuttle-actuating shafts, the forked connecting-rod, and a grooved disk interposed between each 70 shuttle-shaft and a prong of the forked connecting-rod, substantially as set forth.

3. In a duplex-needle machine, in combination, the shaft for driving the needle, the shaft *f* for driving a stationary shuttle, the shafts *f'* and *l* for driving a movable shuttle, (the latter shaft being provided with a telescope-joint,) and a forked connecting-rod *g*, whereby motion is imparted from the needle-shaft to the respective shuttle-shafts, substantially 75 as described.

FERDINAND KERN.
